BUCKLE FASTENER

Fernando M. Ronci, Providence, R. I.

Application April 3, 1939, Serial No. 265,711

15 Claims. (Cl. 24—178)

My invention relates to buckle fasteners, particularly of the type adapted for shoes, gloves and other articles.

My invention particularly relates to the type of buckle fastener having a relatively stationary pivot bar adapted to be attached to the surface of a relatively flat object and a buckle frame pivotally mounted on said pivot bar, so that it may be pivoted upwards for insertion of an opposite strap end therethrough.

My invention in certain respects is an improvement on the invention shown and described in my copending application for patent, Serial No. 203,051, filed April 20, 1938 for Buckle fastener and in general its objects are to carry forward in a more specific form the specific objects of said invention.

One object of my invention therefore is to provide a buckle in which the pivot bar is so constructed as to provide a stationary surface for the rigid attachment of said pivot bar to the strap end of an article to which the buckle is attached, thereby permitting the stitching or other means employed to attach said pivot bar to said article, to overlie said pivot bar without relative movement in use, thereby causing no friction or wear against the surface of the article to which the pivot bar is attached.

In accordance with the principles of said invention, a further object of the present invention is to provide a buckle fastener of this type in which all parts of the buckle, which normally contact the object or strap end to which it is attached will remain stationary without tilting on said article during use and for this purpose I provide a broader type of means than shown in said patent, namely, any type of stop means projecting rigidly forwardly from adjacent the ends of the pivot bar substantially in the plane thereof adapted to abut the surface of the article for this purpose and specifically including the anchor frame characteristic of said invention as well as means projecting rigidly rearwardly from said pivot bar to maintain said pivot bar in a stationary position on the strap end which means may comprise a keeper frame for a strap end desired to be inserted through the buckle. Thus my invention comprises improvements in means to positively prevent the buckle from tilting on said article in use.

A further object of my invention relates to improvements in the stop means I preferably employ to insure that the frame will stop in a substantially vertical position for insertion of a strap end therethrough when it is pivoted rear-

wardly and will rest in a substantially horizontal position in use abutting said anchor frame or stop means projecting rigidly forwardly from said pivot bar spaced from the surface of said article without resting on the surface of the article.

A further object of my invention relates to the specific means I preferably employ including a modified construction of the pivot bar, keeper frame and buckle frame to pivotally mount the arms of the buckle frame adjacent the ends of the pivot bar.

Further features of my invention relate to the specific construction of the parts of the embodiments of my invention shown, which may be readily stamped or otherwise fabricated from sheet material and readily assembled.

These and such other objects of my invention as may hereinafter appear will be best understood from a description of the accompanying drawing, which illustrates embodiments thereof attached to a shoe to function as a shoe buckle.

In the drawing, Fig. 1 is an enlarged plan view of my improved buckle and adjacent parts of the shoe attached to a side wall of a shoe upper with the shoe strap attached to the other side wall of the shoe upper about to be inserted through my improved buckle.

Fig. 2 is a vertical sectional view taken along the line 2—2 of Fig. 1, but with the strap end inserted through the buckle in closed interengaging position with the buckle frame pivoting upwards over the anchor frame, or other stop means employed in use, without touching the shoe as the wearer walks.

Fig. 3 is a perspective view of the buckle per se in detached position with the buckle frame raised to a substantially vertical position for insertion of the strap end therethrough.

Fig. 4 is a disassembled perspective view of the component parts of the embodiment of my invention shown in Figs. 1-3.

Fig. 5 is a perspective view of an alternative form of composite pivot bar and keeper frame I may alternatively employ, employing stop lugs projecting rigidly forwardly from adjacent the ends of the pivot bar in place of the anchor frame employed in the embodiment shown in Figs. 1-4.

In the drawing, wherein like characters of reference indicate like parts throughout, 10 generally indicates a buckle fastener constructed in accordance with my invention.

While I have shown my improved type of buckle fastener employed on a shoe, it is apparent that it may be employed for attaching a strap end to any desired portion of an article of

apparel, or for any other use for which a buckle fastener of this type is desired. It is particularly useful, however, with shoes and gloves and I have shown in the drawing my buckle fastener 5 10 employed on the side wall 12 of a shoe upper, or on a suitable strap 14 projecting inwardly therefrom over the foot instep for use in detachably securing the strap end 18 projecting upwardly from the opposite side wall of the shoe 10 upper thereto to adjustably fasten said strap end 18 within my improved buckle fastener 10 over the instep, further reference being made to the showing of my copending application for Buckle fasteners, Ser. No. 203,051, filed April 20, 1938 15 heretofore referred to.

As stated hitherto, my improved buckle fastener is of a type employing a relatively stationary pivot bar 22 adapted to be rigidly nonrotatably attached to the article below it by suitable 20 means such as the stitching 24 shown attaching said pivot bar 22 to the strap end 14 immediately below it, and a relatively pivotable buckle frame 26 pivotally mounted on said pivot bar 22 to pivot to a position substantially at right angles to the 25 plane of the article below said pivot bar 22 so that the opposite strap end 18 may be inserted underneath the outer end 28 of said buckle frame while being attached and detached to my improved buckle fastener. My improved buckle 30 fastener also includes a buckle tongue 30 also pivotally mounted on said pivot bar 22 having an end adapted to be inserted through a selected hole 32 in the strap end 18 so that the end thereof may be forced by the strap end against 35 the end 28 of the buckle frame 26 as usual when in use, said strap end also functioning to pull the buckle frame downwards substantially to the plane in which the pivot bar 22 is attached to the article. While the buckle frame 26 may be 40 of any desired shape, it is preferably constructed of the hollow rectangular formation shown with the outer end bar 28 and the side bars or arms 34.

My improved buckle is provided with means 45 projecting rigidly rearwardly from said pivot bar 22, which means in my preferred embodiment, comprises a strap end keeper frame 40 adapted in use to receive the tip of the strap end 18 therethrough to clamp the tip of the strap end 18 against the strap end 14 or other article 50 to which the pivot bar 22 of my improved buckle fastener is nonrotatably attached. In my preferred embodiment said keeper frame is also 55 preferably rectangular and includes the flat end bar 42 and the side bars or arms 44 having the ends thereof suitably secured to the main pivot bar 22.

As stated hitherto, a further feature of my invention consists in providing means 50 projecting rigidly forwardly from said pivot bar to function in association with said means or keeper frame hitherto described, projecting rigidly rearwardly from said pivot bar 22 to maintain said pivot bar 22 in a stationary position on said article against tilting when said pivot bar is 60 once secured thereto by the stitching 24 or other means hitherto described, in my preferred embodiment, said means 50 comprising an anchor frame 50 projecting rigidly forwardly from said pivot bar 22 substantially in the plane thereof 65 adapted to abut the surface of the article or strap end 14 in front of said pivot bar. In the embodiment of my invention shown in Figs. 1-4, said anchor frame comprises an end bar 52 and the side bars 54 having the rear ends thereof 70 rigidly attached to said pivot bar 22 substantially 75

in the plane thereof and substantially adjacent the ends of said pivot bar. In the embodiment of my invention shown in Fig. 5, however, said means 50 comprises the stop lugs 50' projecting integrally forwardly from adjacent the ends of 5 said pivot bar substantially in the plane thereof.

My invention specifically relates to the means I preferably employ for pivotally mounting the buckle frame 26 on the pivot bar 22 or adjacent front portion of the keeper frame 40. For this purpose, I provide the filled-in portions 46 adjacent the ends of said arms 44 and said pivot bar 22 and I provide said filled-in portions with the relatively large pivot holes 48 therein. The ends 60 of the pivot arms 34 of the buckle frame 15 pass through said keeper frame holes 48 and are rolled upwardly as at 49 around said pivot bar and the ends thereof substantially circumferentially abut the opposite surface of the pivot arms 34 of said buckle frame 26, to pivotally 20 mount said buckle frame on said pivot bar. As will be apparent the filled-in portions 46 also provide stop means to limit the rearward pivotal movement of said buckle frame 26 in the manner to be described.

As stated hitherto, my invention relates to improvements in the specific type of means employed for limiting the pivoting movement of said buckle frame and in my preferred embodiment shown for this purpose, I preferably specifically provide the arms 34 of said buckle frame with the stop lugs 51 projecting inwardly thereof spaced such a distance from the filled-in stop means portions 46 of said keeper frame as to abut said stop means portions 46 when said 35 buckle frame is pivoted rearwardly substantially to a vertical position for the insertion of the strap end 18 therethrough and also so spaced from the ends of said buckle frame arms 34 to abut the forwardly projecting means 50 or 50' when said buckle frame 26 is pivoted substantially 40 to a horizontal position in use, whether said means projecting forwardly from the pivot bar comprises the anchor frame 50 as shown in Figs. 1-4, or the stop lugs 50' shown for this purpose 45 in Fig. 5.

The buckle tongue 30 may be conveniently mounted on the pivot bar by having the end 31 thereof rolled around the portion of the pivot bar between the aligning lugs 33 integrally stamped thereon for this purpose.

It is thus obvious that inasmuch as the means projecting rigidly rearwardly from said pivot bar, namely, the keeper frame 42 and the means 50 projecting rigidly forwardly from said keeper bar, whether it comprises the anchor frame 50, 55 or the stop lugs 50', both continuously abut the surface of the article 14 so as to substantially prevent any tilting movement of the buckle frame in use and that if the pivot bar 22 be attached directly to the surface of said article as by the stitching 24, that will be substantially free of friction and wearing movement on said article in use.

It is also apparent that from an inspection of the component parts of my improved buckle fastener that they may be readily stamped from flat stock.

It is also apparent that with the particular construction shown, stop means will be provided if desired, to limit the rearward movement of the 70 buckle frame to a substantially vertical position and stop means will also be provided to limit the downward movement of the buckle frame to a substantially horizontal position, yet continuously spaced from the surface of the article on 75

which my improved buckle fastener is mounted so as to prevent wear between the parts of my improved buckle, or the shoe or other article or material below it.

5 It is thus apparent that I have provided a novel type of buckle fastener, constructed of a minimum number of readily formed and assembled parts and with the advantages described above.

10 It is understood that my invention is not limited to the specific embodiments shown and that various deviations may be made therefrom without departing from the spirit and scope of the appended claims.

What I claim is:

15 1. A buckle fastener adapted for use with shoes, gloves and other articles, comprising a pivot bar, an anchor frame having arms projecting rigidly forwardly from adjacent the ends of said pivot bar substantially in the plane thereof adapted to abut the surface of an article, a strap end keeper frame having arms projecting rigidly rearwardly from said pivot bar substantially in the plane thereof to permit insertion of a strap end therethrough to overlie said article having filled-in portions having pivot holes therein adjacent the ends of said arms and said pivot bar, a buckle frame having pivot arms having ends passing through said keeper frame holes and rolled around said pivot bar to pivotally mount said buckle frame on said pivot bar, said arms having stop lugs projecting inwardly thereof spaced such a distance from the filled-in portions of said keeper frame as to abut said portions when said buckle frame is pivoted rearwardly substantially to a vertical position and also to abut said anchor frame arms when said buckle frame is pivoted substantially to a horizontal position in use, a buckle tongue, and means to pivotally mount said buckle tongue on said pivot bar to pivot substantially without lateral sway in a single plane and without movement of said pivot bar, whereby said pivot bar may be permanently rigidly secured to said article against movement in use.

20 2. A buckle fastener adapted for use with shoes, gloves and other articles, comprising a pivot bar, an anchor frame having arms projecting rigidly forwardly from adjacent the ends of said pivot bar substantially in the plane thereof adapted to abut the surface of an article, a strap end keeper frame having arms projecting rigidly rearwardly from said pivot bar substantially in the plane thereof to permit insertion of a strap end therethrough to overlie said article having filled-in portions having pivot holes therein adjacent the ends of said arms and said pivot bar, a buckle frame having pivot arms having ends passing through said keeper frame holes and rolled around said pivot bar to pivotally mount said buckle frame on said pivot bar, said arms having stop lugs projecting inwardly thereof spaced such a distance from the filled-in portions of said keeper frame as to abut said portions when said buckle frame is pivoted rearwardly substantially to a vertical position and also to abut said anchor frame arms when said buckle frame is pivoted substantially to a horizontal position in use and a buckle tongue pivotally mounted on said pivot bar.

25 3. A buckle fastener adapted for use with shoes, gloves and other articles, comprising a pivot bar, an anchor frame having arms projecting rigidly forwardly from adjacent the ends of said pivot bar substantially in the plane thereof adapted to abut the surface of an article, a strap end keeper frame having arms projecting rigidly rearwardly

from said pivot bar substantially in the plane thereof to permit insertion of a strap end therethrough to overlie said article having stop means projecting inwardly therefrom adjacent the ends of said arms and said pivot bar, a buckle frame having pivot arms pivotally mounted on said pivot bar, said arms having stop means projecting inwardly thereof spaced such a distance from said keeper frame stop means as to abut said means when said buckle frame is pivoted rearwardly substantially to a vertical position and also to abut said anchor frame arms when said buckle frame is pivoted substantially to a horizontal position in use and a buckle tongue pivotally mounted on said pivot bar.

30 4. A buckle fastener adapted for use with shoes, gloves and other articles, comprising a pivot bar, stop means projecting rigidly forwardly from adjacent the ends of said pivot bar substantially in the plane thereof adapted to abut the surface of an article, a strap end keeper frame having arms projecting rigidly rearwardly from said pivot bar substantially in the plane thereof to permit insertion of a strap end therethrough to overlie said article having stop means projecting inwardly therefrom adjacent the ends of said arms and said pivot bar, a buckle frame having pivot arms pivotally mounted on said pivot bar, said arms having means projecting inwardly thereof spaced such a distance from said keeper frame stop means as to abut said means when said buckle frame is pivoted rearwardly substantially to a vertical position and also to abut said forwardly projecting stop means when said buckle frame is pivoted substantially to a horizontal position in use and a buckle tongue pivotally mounted on said pivot bar.

35 5. A buckle fastener adapted for use with shoes, gloves and other articles, comprising a pivot bar, stop means projecting rigidly forwardly from adjacent the ends of said pivot bar substantially in the plane thereof adapted to abut the surface of an article, a strap end keeper frame having arms projecting rigidly rearwardly from said pivot bar substantially in the plane thereof to permit insertion of a strap end therethrough to overlie said article having filled-in portions having pivot holes therein adjacent the ends of said arms and said pivot bar, a buckle frame having pivot arms having ends passing through said keeper frame holes and rolled around said pivot bar to pivotally mount said buckle frame on said pivot bar, said arms having lugs projecting inwardly thereof spaced such a distance from the filled-in portions of said keeper frame as to abut said portions when said buckle frame is pivoted rearwardly substantially to a vertical position and also to abut said forwardly projecting stop means when said buckle frame is pivoted substantially to a horizontal position in use and a buckle tongue pivotally mounted on said pivot bar.

40 6. A buckle fastener adapted for use with shoes, gloves and other articles, comprising a pivot bar, a strap end keeper frame having arms projecting rigidly forwardly from adjacent the ends of said pivot bar substantially in the plane thereof adapted to abut the surface of an article, said arms being so spaced from the ends of said pivot bar as to be normally concealed by an overlying strap end in use, a strap end keeper frame having arms projecting rigidly rearwardly from said pivot bar substantially in the plane thereof to permit insertion of a strap end therethrough to overlie said article, a buckle frame adapted to

- receive said strap end therethrough having pivot arms having spaced ends pivotally mounted on the ends of said pivot bar to pivotally mount said buckle frame on said pivot bar, said arms having stop lugs projecting inwardly thereof to abut said forwardly projecting anchor frame when said buckle frame is pivoted substantially to a horizontal position in use and a buckle tongue pivotally mounted on said pivot bar.
10. 7. A buckle fastener adapted for use with shoes, gloves and other articles, comprising a pivot bar, a strap end keeper frame having arms projecting rigidly rearwardly from said pivot bar substantially in the plane thereof to permit insertion of a strap end therethrough to overlie said article having filled-in portions having pivot holes therein adjacent the ends of said arms and said pivot bar, a buckle frame adapted to receive said strap end therethrough having spaced pivot arms having ends passing through said keeper frame holes and rolled around said pivot bar to pivotally mount said buckle frame on said pivot bar, said arms having stop lugs projecting inwardly thereof spaced such a distance from the filled-in portions of said keeper frame as to abut said portions when said buckle frame is pivoted rearwardly substantially to a vertical position and a buckle tongue pivotally mounted on said pivot bar.
15. 8. A buckle fastener adapted for use with shoes, gloves and other articles, comprising a pivot bar, stop means projecting rigidly forwardly from adjacent the ends of said pivot bar substantially in the plane thereof adapted to abut the surface of an article, a strap keeper frame having arms projecting rigidly rearwardly from said pivot bar substantially in the plane thereof to permit insertion of a strap end therethrough to overlie said article having stop means projecting inwardly therefrom adjacent the ends of said arms and said pivot bar, a buckle frame having pivot arms adapted to receive said strap end therethrough pivotally mounted on said pivot bar, said arms having means projecting inwardly thereof spaced such a distance from said keeper frame stop means as to abut said means when said buckle frame is pivoted rearwardly substantially to a vertical position and also to abut said forwardly projecting stop means when said buckle frame is pivoted substantially to a horizontal position in use and a buckle tongue pivotally mounted on said pivot bar.
20. 9. A buckle fastener adapted for use with shoes, gloves and other articles, comprising a pivot bar, a strap end keeper frame having arms projecting rigidly rearwardly from said pivot bar substantially in the plane thereof to permit insertion of a strap end therethrough to overlie said article having stop means projecting inwardly therefrom adjacent the ends of said arms and said pivot bar, a buckle frame adapted to receive said strap end therethrough having pivot arms pivotally mounted on said pivot bar, said arms having stop means projecting inwardly thereof to abut said keeper frame stop means when said buckle frame is pivoted rearwardly substantially to a vertical position and a buckle tongue pivotally mounted on said pivot bar.
25. 10. A buckle fastener adapted for use with shoes, gloves and other articles, comprising a pivot bar, an anchor frame having arms projecting rigidly forwardly from adjacent the ends of said pivot bar substantially in the plane thereof adapted to abut the surface of an article, said arms being so spaced from the end of said pivot bar as to be normally concealed by an overlying strap end in use, a strap end keeper frame having arms projecting rigidly rearwardly from said pivot bar substantially in the plane thereof to permit insertion of a strap end therethrough having pivot arms adapted to receive said strap end therethrough pivotally mounted on said pivot bar, said arms having stop means projecting inwardly therefrom adjacent the ends of said arms and said pivot bar, a buckle frame having pivot arms adapted to receive said strap end therethrough pivotally mounted on said pivot bar, said arms having stop means projecting inwardly thereof to abut said forwardly projecting stop means when said buckle frame is pivoted substantially to a horizontal position in use and a buckle tongue pivotally mounted on said pivot bar.
30. 11. A buckle fastener adapted for use with shoes, gloves and other articles, comprising a pivot bar, stop means projecting rigidly forwardly from adjacent the ends of said pivot bar substantially in the plane thereof adapted to abut the surface of an article, said stop means being so spaced from the ends of said pivot bar as to be normally concealed by an overlying strap end in use, a strap end keeper frame having arms projecting rigidly rearwardly from said pivot bar substantially in the plane thereof to permit insertion of a strap end therethrough to overlie said article having stop means projecting inwardly therefrom adjacent the ends of said arms and said pivot bar, a buckle frame having pivot arms adapted to receive said strap end therethrough pivotally mounted on said pivot bar, said arms having means projecting inwardly thereof spaced such a distance from said keeper frame stop means as to abut said means when said buckle frame is pivoted rearwardly substantially to a vertical position and also to abut said forwardly projecting stop means when said buckle frame is pivoted substantially to a horizontal position in use and a buckle tongue pivotally mounted on said pivot bar.
35. 12. A buckle fastener adapted for use with shoes, gloves and other articles, comprising a pivot bar, stop means projecting rigidly forwardly from adjacent the ends of said pivot bar substantially in the plane thereof adapted to abut the surface of an article, said stop means being so spaced from the end of said pivot bar as to be normally concealed by an overlying strap end in use, a strap end keeper frame having arms adapted to receive said strap end therethrough projecting rigidly rearwardly from said pivot bar substantially in the plane thereof to permit insertion of a strap end therethrough to overlie said article, a buckle frame having pivot arms adapted to receive said strap end therethrough pivotally mounted on said pivot bar, said arms having stop means projecting inwardly thereof to abut said forwardly projecting stop means when said buckle frame is pivoted substantially to a horizontal position in use and a buckle tongue pivotally mounted on said pivot bar.
40. 13. A buckle fastener adapted for use with shoes, gloves and other articles, comprising a pivot bar rigidly directly securable to an underlying article, an anchor frame having arms projecting rigidly forwardly from said pivot bar to abut the surface of said article, said arms being so spaced from the ends of said pivot bar as to be normally concealed by an overlying strap end in use, a strap end keeper frame projecting rigidly rearwardly from said pivot bar to permit the insertion of a strap end therethrough to over-

lie said article with said keeper frame abutting said strap end, a buckle frame having spaced arms adapted to receive said strap end therebetween, means to pivotally mount said buckle frame arms on said pivot bar so that said buckle frame may pivot from a closed position overlying said anchor frame to an open position substantially at right angles to said keeper frame for facile insertion of said strap end therethrough and a buckle tongue pivotally mounted on said pivot bar.

14. A buckle fastener adapted for use with shoes, gloves and other articles, comprising a pivot bar rigidly directly securable to an underlying article, an anchor frame having arms projecting rigidly forwardly from said pivot bar to abut the surface of said article, said arms being so spaced from the ends of the pivot bar as to be normally concealed by an overlying strap end in use, a strap end keeper frame projecting rigidly rearwardly from said pivot bar to permit the insertion of a strap end therethrough to overlie said article with said keeper frame abutting said strap end, a buckle frame having spaced arms adapted to receive said strap end therebetween, means to pivotally mount said buckle frame arms on said pivot bar without movement of said pivot bar so that said buckle frame may pivot from a closed position over-

lying said anchor frame to an open position substantially at right angles to said keeper frame for facile insertion of said strap end therethrough, a buckle tongue, and means to pivotally mount said buckle tongue on said pivot bar to pivot substantially without lateral sway in a single plane and without movement of said pivot bar, whereby said pivot bar may be permanently rigidly secured directly to said article without movement in use.

15. A buckle fastener for use with shoes, gloves and other articles, comprising a pivot bar rigidly directly securable to an underlying article, means projecting rigidly forwardly from said pivot bar so spaced from the ends of said pivot bar as to be normally concealed by an overlying strap end in use and means projecting rigidly rearwardly from said pivot bar to maintain said pivot bar in a stationary position on an article, a buckle frame pivotally mounted on said fastener substantially in the axis of said pivot bar so that said buckle frame may pivot from a closed position overlying said forwardly projecting means to an open position substantially at right angles to said article for facile insertion of said strap end therethrough and a buckle tongue pivotally mounted on said pivot bar.

FERNANDO M. RONCI.
